UNITED STATES PATENT OFFICE.

FRANK W. MILBOURN, OF PAINESVILLE, OHIO, ASSIGNOR TO THE COE MANUFACTURING COMPANY, OF PAINESVILLE, OHIO, A CORPORATION OF OHIO.

MOTOR-OPERATED VENEER LATHE.

Application filed April 19, 1927. Serial No. 184,904.

This invention relates to veneer lathes and has for its primary object to electrify the lathe which results in simplicity of operation and increased efficiency.

5 Another object of the invention is to provide motor actuated means for the dogging and tail spindles so that they may be rapidly moved into engaging or out of engaging position with the log from which the veneer 10 is to be cut.

Another object of the invention is to provide motor actuated means whereby the knife carriage can be moved into and out of cutting engagement with the log independently of the operation of the knife carriage 15 by the main drive shaft.

Another object of the invention is to provide electrical means whereby the knife carriage cannot be actuated by the knife carriage 20 motor operated means when the said knife carriage is being actuated by the main drive shaft.

It is a further object of the invention to provide means in combination with an electric switch whereby when said switch is in closed position, there will be no driving connection between the main drive shaft and the knife carriage but movement of the knife carriage toward or away from the log 30 will be controlled by closing a proper circuit to the carriage feed motor.

Another object of the invention is to provide push button switches mounted upon the lathe at a location convenient to the operator so that the entire operation of the lathe 35 can be controlled from one point.

With the objects above indicated and other objects hereinafter explained in view, my invention consists in the construction and 40 combination of elements hereinafter described and claimed:

Referring to the drawings:

Fig. 1 is a vertical rear view of the lathe or the operator's side of the lathe.

45 Fig. 2 is an end view of the dogging end of the lathe.

Fig. 3 is a top plan view of the tail spindle end of the lathe showing the position of the spindle motor and the carriage feed motor.

50 Fig. 4 is a fragmentary top plan view of the circuit breaker switch actuated by the clutch lever.

Fig. 5 is a diagram of the wiring of the independent motors.

55 In the drawings, 10 and 11 indicate, re-

spectively, a pair of standards, triangularly shaped, and of box construction which are connected together in spaced vertical relation by spacers 12, three being herein shown extending from the respective apexes of the 60 standards.

Each of the standards 10 and 11 suitably supports a pair of horizontally movable spindles in a manner to be hereinafter described, the dogging spindle being indicated 65 by 13 and the tail spindle being indicated by 14. As each of these spindles is mounted in the same manner, the description of one mounting will suffice for both.

The front or log side of the standards 10 70 and 11 is provided with a transverse recess 15 which receives and supports a spindle sleeve 16, the latter being clamped loosely within the transverse recess 15 by caps 17 suitably bolted to the face of the standards. 75 The spindles 13 and 14 are exteriorly screw-threaded and extend through the sleeve 16, the latter being provided with a depending tongue or spline 18 engageable with a co-operating groove or spline 19 extending 80 throughout the length of the spindle. This arrangement permits the spindles 13 and 14 to be moved longitudinally in either direction within the sleeve 16 but prevents relative rotation between the spindles and 85 sleeves.

To impart movement to the spindle, a spindle driving sleeve 20 interiorly screw-threaded engages the screw-threads of the spindle and is rotatably mounted within a 90 locking member 21 which is suitably bolted to the spindle sleeve 16. This spindle driving sleeve 20 has securely mounted upon its free end a sprocket wheel 22 and beyond the latter a hand wheel 23 which when either 95 are rotated is adapted to rotate the spindle driving sleeve 20 to cause longitudinal movement of the spindle 14 in either direction depending upon the direction of rotation of the sprocket wheel or hand wheel. It will, 100 therefore, be seen that to reciprocate the spindles toward or away from each other, or into and out of engagement with the log from which the veneer is cut, the sprocket wheel 22 or the hand wheel 23 is rotated 105 in the proper direction. It should be understood that separate sprocket wheels are provided for actuating the dogging spindle 13 and the tail spindle 14 as clearly shown in Fig. 1 and the spindle driving sleeve for 110

reciprocating the dogging spindle 13 has secured thereto a brake drum 24 with which is adapted to engage a brake band 25 partially surrounding the drum and having one end 5 suitably secured to the standard 11 while the opposite end is connected to a bell crank lever 26 pivotally connected at 27 to the upper portion of the standard. The bell crank lever has a handle portion 28 adapted 10 to be grasped by the operator of the lathe to stop rotation of the spindle driving sleeve of the dogging spindle 13 when desirable.

When the dogging spindle 13 and tail spindle 14 are each in engagement with the 15 log, it is necessary to impart rotary motion to the log so that the veneer may be cut therefrom. This is accomplished by providing a pair of bull gears 29 which are positioned within suitable slots 30 in the 20 face of each standard and securely supported upon the spindle sleeves 16. These bull gears 29 are keyed or otherwise secured to the spindle sleeves 16 so that upon rotation imparted to the bull gears, the log is 25 rotated in the proper direction due to non-rotative relative engagement between the spindle sleeves 16 and the spindles 13 and 14.

A main power shaft 31 extends horizontally adjacent the lower portion of the 30 standards and is secured thereto in suitable bearings 32 provided upon the face of the standards. This shaft 31 has keyed thereto a pair of pinions 33 as indicated by dotted lines, Figure 2 which engage with the bull 35 gears 29 to rotate the latter upon rotation of the main power shaft 31, actuated from any suitable source of power. It will be readily understood from the foregoing description then that the log from which the veneer is 40 cut is rotated while the veneer is being cut therefrom by causing rotation of the main drive shaft 31 and that the reciprocation of the spindles 13 and 14 is independent thereof.

Heretofore the dogging spindle 13 and tail spindle 14 have been actuated by power 45 actuated means and by a hand wheel respectively, such as 23 for moving the chucks carried by the spindles into and out of engagement with the log as desired but the operation in this manner was very slow and it was somewhat difficult to disengage the chucks from the log. The sprocket wheels 50 22 have, therefore, been employed for reciprocating the dogging spindle and tail spindle which is actuated by a chain 34 driven by independent motors 35 and 36 connected in suitable circuits. These motors are of the reversible type and the direction 55 of rotation of the armature is controlled by suitable push buttons in series with the motors and attached upon the standard 11 in a position convenient to the operator.

The push button switch 37 controls the 60 circuit to the tail spindle motor 35 while

the push button switch 38 controls the circuit to the dogging spindle motor 36. When one button on the switch 38 is depressed, the motor 36 is actuated to move the dogging spindle in one direction and when the other button, of the same switch is depressed, the spindle is moved in the opposite direction. The same condition exists when the push buttons of the switch 37 are depressed to 70 actuate the motor 35, the tail spindle 14 being reciprocated in one direction or the other.

A carriage 39 which supports the veneer cutting knife is slidably mounted upon guides 40 extending inwardly from each side 80 of the standards 10 and 11 and can be either attached thereto or formed integrally therewith. This carriage 39 is moved toward and away from the log suspended between the spindles 13 and 14 by threaded shafts 40^a 85 which engage with threaded sleeves 41 provided at opposite ends of the carriage. When the shafts 40^a are rotated in one direction, the carriage 39 carrying the knife is moved into cutting position with the log 90 and when rotated in the opposite direction, the carriage is moved away from the log. The shafts 40^a are suitably journalled in bearings 42 formed integrally or otherwise secured to the standards 10 and 11 and have 95 keyed or pinned to the end beyond the bearings bevel gears 43. A pair of vertically extending shafts 44 are journalled in extensions or bearings 45 formed integral with the standards 10 and 11 and the upper ends 100 of the shafts are provided with bevel pinions 46 which are in mesh with the bevel gears 43 on the shafts 40^a.

The lower ends of the shafts 44 are provided with bevel gears 47 which mesh with bevel gears 48 suitably secured to a horizontally extending carriage feed shaft 49 which latter has its outer portions rotatably mounted in the standards 10 and 11. It will, therefore, be evident that when the carriage feed shaft 49 is rotated, the knife carriage 39 will be moved toward or away from the log through the bevel gear arrangement depending upon the direction of rotation of the shaft. Rotation is imparted to the carriage feed shaft 49 by a motor 50 connected thereto by a chain 51 which engages suitable sprockets secured to the shaft and motor respectively.

The motor 50 is connected in a circuit in 110 series with a push button switch 52 mounted adjacent the switches 37 and 38 which is adapted to reverse the direction of rotation of the motor by depressing the proper button.

It should be here pointed out that this carriage feed shaft 49 is rotated by actuation of the motor 50 for causing the carriage to move toward and away from the log independently of the main drive shaft 115 120 125 130

31 to which it is connected through suitable gearing and clutch mechanism which will be hereinafter explained.

The end of the shaft 49 within the standard 11 is provided with a slideable sleeve 53 having rearwardly extending projections or teeth 54 which are adapted to engage with cooperating recesses 55 provided in the hub of a gear 56 loosely mounted on the end of the shaft 49 journaled in the standard 11. This sleeve, constituting a slideable clutch, is moved into engagement with the gear 56 by a lever 58 and pivoted at 59 to the outside of the standard 11. The lever extends upwardly to a position adjacent the control push buttons convenient to the hand of the operator, and when moved to the right, as shown in Fig. 1, the clutch is disengaged and the carriage can only be moved by depressing the push button switch 52. When the lever is moved to the left of that shown in Fig. 1, the sleeve 54 is moved into engagement with the gear 56 and the carriage is moved inwardly toward the log through a series of gears, indicated generally by 60, actuated from the bull gear 29 driven from the main drive shaft 31. The gear ratio 60 is selected so that the carriage 37 carrying the knife will be moved into cutting engagement with the log in proportion to the speed at which the log is being rotated.

It is important that the carriage 39 can be moved toward and away from the log independently of the main drive shaft and without cutting off the power to the main drive shaft. This is accomplished by the clutch mechanism including the sleeve 53 and gear 56 but it is essential that means be provided wherein when the carriage is being moved from the main shaft, the push button switch 52 will not have any effect upon the motor 50 for moving the carriage and vice versa.

A circuit breaker switch 61 is therefore mounted upon the standard 11 convenient to the lever 58 and has a movable switch arm 62 engageable with the lever when the latter is moved so as to disengage the clutch as clearly shown in Fig. 1. This switch 61 is in series with the motor 50 and push button switch 52 and when engaged by the lever, the switch is closed thereby rendering the motor operative upon depression of either of the push buttons of the switch 52. When the lever is moved to the left so as to move the sleeve 53 into engagement with the gear 56 to cause the carriage to be moved by the power of the main drive shaft 31, the switch arm 62 is moved outwardly by a spring within the switch 61 which opens the circuit to the motor 50 thereby rendering the latter inoperative in which condition it remains until the lever is again moved into engagement with the switch arm 62. The lever 58 is maintained in switch engaging position

by a recess 63 provided in a bracket 64 bolted to the standard 11 and which also supports the switch 61.

In the wiring diagram shown in Fig. 5, the circuits for the dogging spindle motor and the carriage feed motor are shown but because the circuit for the tail spindle motor is identical with the circuit for the dogging spindle motor and independent thereof, it is not believed necessary to illustrate and explain this circuit separately as the explanation of the dogging spindle motor circuit will suffice for both circuits.

The dogging spindle motor 36 has three conductor wires 64, 65 and 66 suitably connected thereto and leading therefrom to a plurality of contact fingers. A triple knife switch 67 normally biased towards open circuit position has its terminals connected to conductor wires 68, 69 and 70, the wires 68 and 70 being connected to one side of the main line while the wire 69 is connected to the other side of the main line. The switch 67 is moved to closed circuit position by energizing a solenoid 71 which has one terminal connected by a wire 72 to the conductor wire 69 and the other terminal connected by a wire 73 to the "out" push button of the switch 38. A return wire 74 is connected between the "out" push button and the conductor wire 70 which completes the circuit for actuating the dogging spindle motor 36 in one direction and the circuit is closed by depressing the "out" push button of the switch 38. To reverse the direction of rotation of the motor 36, the wires 75, 76 and 77 are suitably connected as shown in Fig. 5 to the conductor wires 66, 64 and 65, respectively, and to a plurality of contact fingers. A triple knife switch 78 is normally biased toward open circuit position and the terminals are connected by wires 79, 80 and 81 to the conductor wires 70, 69 and 68, respectively. The switch 78 is moved into closed circuit position by energizing of solenoid 82 having one terminal connected by a wire 83 to the "in" push button of the switch 38 while the other terminal is connected by a wire 84 to the wire 69 leading to the main line. The "in" push button is connected to the return wire 74 and this completes the circuit for reversing the motor.

The wiring for the circuit of the carriage feed motor is also the same as the wiring of the dogging spindle motor with one exception and it is, therefore, believed that explanation of this wiring is unnecessary except as to the change.

As heretofore described, a circuit breaker switch 61 is employed for controlling the circuit of the carriage feed motor so that the knife carriage 39 cannot be moved thereby in either direction so long as it is connected through the gear mechanism with the main drive shaft 31.

The return wire 74 as shown in the wiring diagram for the dogging spindle motor 36 is not connected by a common return to the wire 70 leading to the main line but instead is connected to one terminal of the circuit breaker switch 61. A wire 85 is connected to the other terminal of the circuit breaker switch 61 and to a terminal of "in" and "out" buttons of the push button switch 10 52 which controls the direction of rotation of the carriage feed motor 50 and as long as the lever 58 is in engagement with the arm 62 of the circuit breaker switch 61, the motor 50 can be actuated by depressing either 15 the "in" or "out" button depending upon the desired direction of movement of the carriage. However, when the lever is moved out of engagement with the circuit breaker arm 62, the circuit is opened and the motor 20 cannot be actuated by either of the push buttons of the switch 52.

It should be understood that the particular wiring employed in connection with the motors is of no particular importance as any 25 other wiring might be employed with as good results.

Having thus described my invention, I claim:

1. In a veneer lathe, a tail spindle adapted 30 to be moved into engagement with the end of a log, a dogging spindle adapted to be moved into engagement with the opposite end of the log for securing the same between the spindles, means for supporting said spindles, and independently operated motors for actuating said tail spindle and said dogging spindle.

2. In a veneer lathe, a tail spindle adapted 40 to be moved into engagement with the end of a log, a dogging spindle adapted to be moved into engagement with the opposite end of the log for securing the same between the spindles, means for supporting said spindles, independently operated motors for actuating said tail and dogging spindles, and controlling means for said motors mounted upon the back of the lathe.

3. In a veneer lathe, a tail spindle adapted 50 to be moved into engagement with the end of a log, a dogging spindle adapted to be moved into engagement with the opposite end of the log for securing the same between the spindles, means for supporting said spindles, independently operated motors for actuating said tail spindle and said dogging spindle, controlling means for said motors, a knife carriage adapted to be moved toward and away from said tail spindle and said dogging spindle, and an independently operated motor for actuating said carriage.

4. In a veneer lathe, a tail spindle adapted 60 to be moved into engagement with the end of a log, a dogging spindle adapted to be moved into engagement with the opposite end of the log for securing the same between

the spindles, means for supporting said spindles, independently operated motors for actuating said tail spindle and said dogging spindle, a knife carriage adapted to be moved toward and away from said tail spindle and said dogging spindle, an independently operated motor for actuating said carriage, and controlling means for each motor mounted upon the back of the lathe. 70

5. In a veneer lathe, a tail spindle and a 75 dogging spindle adapted to be moved toward and away from each other and adapted to support a log therebetween, independently operated motors for actuating said tail spindle and said dogging spindle, means for rotating said tail spindle and said dogging spindle in unison, a knife carriage adapted to be moved toward said tail spindle and said dogging spindle by the last mentioned means, means for actuating said carriage from the last mentioned means, a clutch for disengaging the carriage actuating means, and an independently operated motor for reciprocating the knife carriage 80 when said clutch is disengaged. 85

6. In a veneer lathe, a tail spindle and a dogging spindle adapted to be moved toward and away from each other and to support a log therebetween, independently operated motors for actuating said tail spindle and said dogging spindle, means for rotating said tail spindle and said dogging spindle in unison, a knife carriage adapted 90 to be moved toward said tail spindle and said dogging spindle by the last mentioned means, means for actuating said carriage from the last mentioned means, a clutch for disengaging the carriage actuating means, an independently operated motor for reciprocating the knife carriage when said clutch is disengaged, and means actuated by the clutch for preventing operation of the carriage motor when said clutch is in engaged position with the carriage actuating means. 100

7. In a veneer lathe, a dogging spindle, a tail spindle, independent motor operated means for moving said spindles towards and away from each other, a main drive shaft, means for rotating said spindles in unison 115 by said main drive shaft, a knife carriage, gear mechanism between said carriage and said main drive shaft for moving the former towards said spindles, a clutch for disengaging said carriage from said main drive shaft for moving the former towards said spindles, a clutch for disengaging said carriage from said main drive shaft, and an independent motor for reciprocating said carriage when said clutch is in disengaged position. 120

8. In a veneer lathe, a main drive shaft, a pair of log engaging spindles consisting of a tail spindle and a dogging spindle adapted to be rotated in unison from said main drive 125

shaft, means for moving said log engaging spindles into and out of log engaging position, independent motors for actuating said last mentioned means, control means for each of said motors, a knife carriage adapted to be moved into cutting engagement with the log supported between said log engaging spindles and driven from said main drive shaft, a clutch for disengaging 10 said main drive shaft from said carriage, an independent motor for reciprocating said carriage when said clutch is in disengaged position, means actuated by said clutch when in disengaged position for permitting 15 movement of said carriage by said motor, and control means for said motor.

9. In a veneer lathe, a main drive shaft, a pair of log engaging spindles including a tail spindle and a dogging spindle adapted

to be rotated in unison from said main drive 20 shaft, means for moving said log engaging spindles into and out of log engaging position, independent motors for actuating said last mentioned means, control means for each of said motors, a knife carriage adapted 25 to be moved into cutting engagement with the log supported between said log engaging spindles and driven from said main drive shaft, a clutch for disengaging said main drive shaft from said carriage, an independent motor for reciprocating said carriage when said clutch is in disengaged position, and means for preventing movement of said carriage by said motor when 30 said clutch is in engaged position. 35

In testimony whereof, I hereunto affix my signature.

FRANK W. MILBOURN.
